C. KOPPMAN

CAP

Filed Nov. 8, 1921

UNITED STATES PATENT OFFICE.

CHARLES KOPPMAN, OF NEW YORK, N. Y., ASSIGNOR TO THE CAPANHAT CO. INC.,
A CORPORATION OF NEW YORK.

CAP.

Application filed November 8, 1921. Serial No. 513,753.

To all whom it may concern:

Be it known that I, CHARLES KOPPMAN, a citizen of the United States of America, and a resident of New York, county of Bronx, 5 and State of New York, have invented certain new and useful Improvements in Caps, of which the following is a specification.

The present invention relates to caps, particularly those used by men or boys, and 10 has for its object to provide a construction which will permit the cap to be easily and conveniently adjusted to different sizes, whereby the manufacture of caps may be considerably simplified.

My invention is illustrated in the accompanying drawing in which similar reference characters denote corresponding parts and in which Fig. 1 is a bottom plan view of my 15 novel cap; Fig. 2 a perspective view thereof; Fig. 3 a longitudinal section on line 3—3 of Fig. 2 somewhat enlarged; Fig. 4 an inner view of a part of the cap and Fig. 5 an enlarged cross section on line 5—5 of Fig. 4.

Referring to the drawing more in detail 20 10 denotes a cap which as usually is provided with a peak 11 and means such as press button 12 and eyelet 13 or the like whereby the front part of the crown may be fastened in a downwardly folded position 30 to the peak.

To the outer face of the crown near the lower edge thereof and a suitable distance away from the ends of the attached edge of the peak are sewed or otherwise attached 35 two straps 15, 16 of suitable material such as cloth or the like which are adapted to be folded over the front lower part of the crown near the upper edge of the peak and which are provided at their free ends with 40 suitable tightening means, whereby the two straps can be adjustably fastened together after the cap is expanded or contracted to the particular size desired.

For the tightening of the straps various 45 means of known construction may be used. In the present embodiment of my invention an ordinary buckle 17 may be provided which is fastened to the free end of one of the straps. The two straps are so admeasured in length 50 that the buckle 17 will be located in about the center of the front lower part of the crown so as to be entirely concealed between the downwardly folded part of the crown and the peak. The attachment points 14 of the straps 15, 16 are each located at a dis-

tance from the ends of the attached edge of the peak sufficient to allow several variations in size. The lower inner part of the crown is reinforced by a member 18 of semi-rigid material, as a band of cardboard or 60 the like and which is concealed by the lining 19. This reinforcing strip or band which extends around the inner face of the rim is cut away at points opposite the attachment points 14 of the straps so that the parts of 65 the crown between these points 14 and the peak remain soft and can be gathered or puckered to reduce the size of the cap.

The band 20 which is usually sewed to the lower edge of the crown and folded inwardly 70 around the reinforced rim of the cap, in the present construction is split in front, and its stitches 20' whereby it is attached to the crown extend only to the attachment points 14 of the straps. The end portions 20² of 75 said band are passed through vertical slots or recesses 10' in the crown, located a distance substantially equal to or slightly larger than the distance between the points 14 and the peak and adapted to be concealed by the 80 folded part of the crown when attached to the peak. These end portions 20² are attached to the straps 15 so that when drawn together by the tightening of the 85 straps, will contract the rim of the crown to 90 the desired extent causing the flexible or soft parts between the points 14 and the peak to be gathered up or puckered as shown at 22. The slots or recesses 10' are arranged transversely of the rim portion of the cap 95 and are of a length about equal to the width of said rim portion to hold the end portions of said band 20 in tangential relation to the latter, so that when said end portions 20² are drawn together by the tightening of the 100 straps, the rim portion only will be contracted and therefore the puckering or gathering of the material will be confined to that portion.

In order that the plaits formed by the 100 gathering of the material may be of uniform pretetetermined shape, a loop shaped band 23 of some flexible material, as ribbon or the like, is attached at 23' to the inner face of each strap and is passed in a zig-zag manner 105 through two or more slots or recesses 10², 10³ cut in the part of the crown adapted to be gathered up (Fig. 3). When by the tightening of the straps the end portions 20² of the band are drawn together, the parts of 110

the rim between the attachment point 14 and the corresponding sides of the peak 11 will be gathered into plaits of a width equal to the distances between the slots 10³, 10³.

5 Thus by the above described construction the cap may be easily and conveniently adjusted to fit various sizes, while the means for adjustment are well concealed from view and therefore do not affect the general appearance of the cap.

10 Since various modifications may be made in the construction without departing from the principle of my invention I do not wish to restrict myself to the details shown 15 and described.

What I claim and desire to secure by Letters Patent is:—

1. A cap having a peak, a rim a part of 20 which only is reinforced, the non-reinforced parts being located at the sides of said peak, said non-reinforced parts having several transversely extending slots, a band attached to the inner face of the reinforced part of 25 the rim and having end extensions passing outwardly each through one of said slots, straps attached to the outer face of said rim at the ends of the reinforced part thereof and having means for tightening said straps together, the outwardly passing ends of said 30 extensions being attached to said straps so that on tightening the latter, the non-rein-

forced parts of said rim will be gathered to form plaits and means for causing said plaits to arrange themselves uniformly and in a predetermined fashion. 35

2. A cap having a peak, a rim a part of which only is reinforced, the non-reinforced parts being located at the sides of said peak, said non-reinforced parts having several transversely extending slots, a band attached to the inner face of the reinforced part of the rim and having end extensions passing outwardly each through one of said slots, straps attached to the outer face of said rim at the ends of the reinforced part thereof, and having means for tightening said straps together, the outwardly passing ends of said extensions being attached to said straps, so that on tightening the latter the non-reinforced parts of said rim will be gathered to form plaits, and loops attached to said straps and passed in zig-zag through the other slots on the corresponding sides of the rim to cause said plaits to arrange themselves uniformly and in a predetermined fashion. 45 50 55

Signed at New York, this 7th day of November, 1921.

CHARLES KOPPMAN.
